UNITED STATES PATENT OFFICE.

MICHAEL J. SHERRY, OF UTICA, NEW YORK.

SHUFFLEBOARD CONSTRUCTION.

Application filed February 26, 1927. Serial No. 171,352.

My present invention relates to shuffleboard construction.

The purpose of my invention is to provide a shuffleboard construction wherein transversely extending reinforcements or stiffening members are provided of sufficient stiffness and so connected to and combined with the wooden shuffleboard proper as to prevent warping or other transverse distortion of the shuffleboard.

It has long been recognized that the tendency to warp is the greatest defect in the usual good quality shuffleboards. The standard width of shuffleboard is eighteen inches while its thickness is usually about two inches. This relatively great width especially when the board is made of solid plank extending the full width of the shuffleboard subjects the board to warping due to the usual variations in the amount of moisture in the air according to the weather. Many of the boards furthermore are placed in basements of clubs or other buildings where there is more than the usual amount of moisture which location further tends to produce transverse warping of the boards notwithstanding the use of apparently solid supporting members or frame work for the board. My aim is to overcome the tendency of the shuffleboards to warp even under the most severe conditions by providing a considerable number of transversely extending re-inforcing or stiffening members engaging the bottom surface of the board and of sufficient rigidity to hold the board from warping, the board and the stiffening members being so formed and connected that the board will be absolutely held from warping by its rigid connection to the stiffening members.

A further purpose is to provide a construction of the type mentioned of such form, construction and co-operation that said reinforcement may be readily applied either to new boards or to old boards and to have the parts of the re-inforcing means simple and strong and economical in cost.

A further purpose is to provide a re-inforcing means and construction of using the same which can be readily used at the center joint of the two planks forming a board. Such central joint has heretofore been one of the places most subject to warping and

the point where warping causes the greatest trouble in that one plank is raised above the other producing an edge that has to be cut down.

Further purposes and objects of my invention will appear from the specification and claims herein.

Fig. 1 is a view partly in side elevation and partly in longitudinal section of a portion of a shuffleboard embodying my invention.

Fig. 2 is a transverse sectional view on line 2—2 of Fig. 1.

Fig. 3 is a longitudinal sectional view through the middle joint portion of a shuffleboard embodying my invention.

Referring to the drawings in a more particular description, it will be seen that my invention is illustrated in combination with a shuffleboard proper composed of the usual two solid thick planks 5 which may be of a standard width as eighteen inches and of the usual thickness, namely two inches, and of any desired or standard length which is usually about thirty feet in length. The usual end trough 6 is formed by end uprights 7 and end projecting cleats 8 and the usual side troughs 9 are formed by the upright side boards 10 and bottom trough pieces 11.

Spaced about evenly along the full length of each of the shuffleboard planks 5 there are provided transversely extending T-shaped slots 12 extending in from the bottom surface 13 of the shuffleboard. This T-shaped slot will in practice be made by forming the upright portion 14 thereof first so as to have it extend into the plank about half the thickness of the board. Then the two oppositely extending horizontally arranged recesses 15 are milled out at the inner end of the upright to form the head of the T-shaped slot mentioned. This T-shaped slot extends the full width of the board and its head portion is of a width and height to snugly receive the strong rigid metal bar 16. Spaced along the middle of the bar 16 are a suitable number of vertically arranged screw-threaded holes 17.

It will be noticed that the making of the T-shaped slots will leave opposite the upright part of the T and below the recesses 15 two strong oppositely facing tongues 18.

These tongues extend the whole width of the board and project from the remaining solid board longitudinally of the board, that is in the line of the grain of the wood.

5 Below each of these T-shaped slots there is placed and held a strong channel bar 19. The flat base 20 of this channel bar straddles the opening in the bottom of the board made by the T-shaped slot and extends on the opposite sides thereof below the tongues 18 and the opposite webs 21 of the channel bar depend from the base and are of sufficient thickness and depth to make the channel bar able to entirely resist any tendency of the 10 board to warp when the adjacent section of the board is rigidly fastened to the channel bar.

The channel bar and board are securely and rigidly attached to each other by a series of headed bolts 22 the shanks of which project up through apertures provided in the base of the channel bar and thereafter extend up through the upright portion 14 of the slot and into the aligned screw-threaded holes 17 provided in the flat metal bar 16. It will be seen that these parts may be readily assembled in an obvious manner and that by tightening up the bolts 22 the oppositely disposed strong tongues 18 of the 20 plank 5 will be clamped between the bar 16 and the channel bar 19. The two tongues 18 so clamped to the channel bar extend the full width of the shuffleboard. These tongues constitute such a large part of the thickness 25 of the shuffleboard and as they project lengthwise or in the grain of the board are so stiff that the shuffleboard for some distance in its length each side of the channel bar is absolutely held from warping.

40 A sufficient number of such channel bars and other cooperating parts will be used and spaced evenly along the length of the shuffleboard as to prevent warping anywhere in the board. In practice I have found that having such a channel bar about every twenty-two inches is sufficient.

The same metal parts which constitute the holding means will be used at the center joint where the two planks 5 meet as shown 45 in Fig. 3. As the ends of the plank are available, however, for making the horizontal recesses 15 without first making the upright portion 14, the said upright portion of the slot will be dispensed with and simply small 50 semi-circular pockets 23 placed at opposite points in the two planks in proper position to receive therethrough the bolts 22. The metal holding means will then be applied as already mentioned and will grasp the 55 tongues 18 projecting from the opposite meeting ends of the two planks of the shuffleboard. It will be seen that the engaged 60 end of each plank will thus be effectively kept from warping and furthermore that the 65 two meeting ends of the planks will be kept

in alignment so that there will never be need to trim either plank to eliminate a shoulder due to one plank warping more than the other.

What I claim as new and desire to secure 70 by Letters Patent is:

1. A shuffleboard construction consisting of a wood shuffleboard having in the bottom thereof a T-shaped slot extending transversely of the board and with the head of the T intermediate the top and bottom of the board and leaving oppositely disposed tongues adjacent the lower surface of the board, a rigid metal bar in the head of said slot, a rigid reinforcing metal member engaging the bottom surface of the board below said bar and means for rigidly connecting said bar and said bottom metal member and clamping said tongues therebetween. 75

2. A shuffleboard construction consisting 80 of a wood shuffleboard having in the bottom thereof a T-shaped slot extending transversely of the board and with the head of the T intermediate the top and bottom of the board and leaving oppositely disposed tongues 85 adjacent the lower surface of the board, a rigid metal bar in the head of said slot, a rigid re-inforcing metal member having stiffening depending flanges engaging the bottom surface of the board below said bar 90 and means for rigidly connecting said bar and said bottom metal member and clamping said tongues therebetween. 95

3. A shuffleboard construction consisting 100 of a wood shuffleboard having in the bottom thereof a T-shaped slot extending transversely of the board and with the head of the T intermediate the top and bottom of the board and leaving oppositely disposed tongues 105 adjacent the lower surface of the board, a rigid bar in the head of said slot, a channel bar engaging the bottom surface of the board below said slot and having its webs depending from the board and headed bolts rigidly connecting said channel bar 110 and said other bar and clamping said tongues of the board rigidly to said channel bar. 115

4. A shuffleboard construction consisting 120 of a wood shuffleboard having in the bottom thereof a plurality of spaced T-shaped slots extending transversely of the board and with the heads of the T's intermediate the top and bottom of the board and leaving at each slot a pair of oppositely disposed 125 tongues adjacent the lower surface of the board, a rigid bar in the head of each T slot, a channel bar engaging the bottom surface of the board below each slot and with its flanges depending below the board and screw-threaded means for rigidly connecting 130 said channel bar and said other bar whereby the tongues of the board are rigidly clamped to said channel bars. 135

5. A shuffleboard construction consisting 130

of a wood shuffleboard having intermediate ber at a plurality of points and clamping the
its top and bottom surfaces a slot extend- wood therebetween to the said bottom mem-
ing transversely of the board, a rigid bar in- ber. ¹⁰
said slot, a rigid re-inforcing metal member In witness whereof I have affixed my sig-
engaging the bottom surface of the board nature this 19th day of February, 1927.
